UNITED STATES PATENT OFFICE.

GUNNAR CHRISTIAN EKSTRÖM, OF STOCKHOLM, AND BROR ANDERS EMIL JOHNSON, OF APPELVIKEN, SWEDEN, ASSIGNEES TO AKTIEBOLAGET GERH. AREHNS MEKANISKA VERKSTAD, OF STOCKHOLM, SWEDEN, A CORPORATION OF SWEDEN.

MEANS FOR PORTIONING CIGARETTES OR OTHER STAFF-SHAPED ARTICLES FOR THE PACKING OF THE SAME.

Application filed August 29, 1925, Serial No. 53,420, and in Sweden June 9, 1923.

This invention relates to a device for portioning cigarettes or other staff-shaped articles for the packing of the same in boxes or the like. According to the invention the cigarettes are fed from one or more magazines through two or more channels or guide-ways to an assembling place, which is common to the said guide-ways and at which the guide-ways are substantially horizontal and located above each other, so that the cigarettes are arranged into two or more parallel rows, located above each other. A suitable number of cigarettes in each row, which cigarettes together constitute a set of cigarettes to be packed in a box, is then pushed from the said guide-ways by a piston and preferably into a chamber, in which the said set is compressed to a compact bundle before the set is introduced into the box. With the portioning device means may be combined for supplying one or more coupons, photos or the like to each set of cigarettes in order to be incorporated with the same.

Fig. 1 in the accompanying drawing shows in a side view a portioning device arranged in accordance with this invention. Fig. 2 shows in a side view a piston for pushing the set of cigarettes out from the guide-ways. Fig. 3 shows in a side view means for locking the superposed cigarettes in each guide-way, while the set of cigarettes is pushed from the assembling place. Fig. 4 shows in a side view means for feeding coupons or the like into the sets of cigarettes.

In the portioning device shown in the drawing three channels or guide-ways 2, 3 and 4 extend downwards from a magazine 1 containing cigarettes, into which guide-ways the cigarettes are fed in the known manner by rotating drums 5, 6 and 7 respectively provided in their peripheral surfaces with grooves. The said guide-ways 2, 3 and 4 meet at their lower ends in such manner, that their lower parts, which are substantially horizontal, are located above each other and the cigarettes descending through the guide-ways constitute in the said horizontal parts of the guide-ways three rows of cigarettes located above each other as shown in Figs. 1 and 3. A suitable number of cigarettes in each row is then pushed longitudinally of the cigarettes out from the guide-ways by a piston 8, Fig. 2, which is provided with tongues

9, adapted to enter the respective guide-ways. Piston 8 is movable in guides and is pushed into the guide-ways by a spring 10 and removed from the same by a cam-disc 12, provided on a rotating shaft 11, and a motion transmitting device 13, 14.

In order to prevent the cigarettes from sliding downwards in the guide-ways 2, 3 and 4 and occupying an oblique position, while the piston 8, after it has removed the cigarettes from the horizontal parts of the guide-ways, is returned, three bars 15, 16 and 17 are provided, Fig. 3, which during the return stroke of the piston are forced against that cigarette of each row, which is located nearest to those cigarettes which are pushed from the guide-ways, and thus lock the said cigarette and all subsequent cigarettes in the guide-ways. The said bars are carried by pivotally mounted bell-crank levers 18, 19 and 20 respectively. Lever 18 is acted upon by a spring 18¹ and a cam-disc 21 by means of an arm 22. Motion is transmitted from the lever 18 to the lever 19 by a link 23, and the bell-crank lever 20 is swung by the lever 19 by means of toothed segments 24 and 25. As the set of cigarettes is pushed from the guide-ways by the piston 8, the cigarettes may enter a chamber, in which the said set is compressed into a compact bundle in order to be then introduced into the box or the like. As the compression chamber, which may be of any suitable or known construction, is not comprised by this invention, it is not shown in the drawing.

Owing to the fact that the cigarettes are brought together into a set from two or more guide-ways simultaneously the gathering of the sets, each composed by a plurality of rows, is effected very rapidly, which considerably increases the output of the packing machine.

For supplying each set of cigarettes with one or more coupons or the like a slot 26, Fig. 1, is provided in one of the walls of the guide-ways, into which the coupon is pushed and thus, in the present case, will be located between two rows of cigarettes. The said coupon is pushed from the said slot simultaneously with the set of cigarettes by a tongue 9^x provided on the piston 8. Coupons are provided in a magazine 27 and are fed from the same by a catcher 28, pivotally

mounted on a slide 30 which is reciprocated in a guide 29. The said catcher 28 is held by a spring 31 in an adjusted position, determined by a screw 32, and so adapted that 5 the catcher during the reciprocation of the slide 30, will engage the lowermost coupon (or it may be two or more coupons) in the magazine 27. While the slide is moved toward the right the caught coupon slides on 10 the top side of the guide of the slide 30. As the slide 30 has been moved through a distance substantially equal to the length of a coupon, it is returned, the coupon being engaged and held in its position by a pawl, 15 fixed on the guide of the slide and consisting of a plate-spring 33 having a knee. The other end of the said spring 33 is adapted to force the coupon against its guide. As the slide 30 is again moved toward the right 20 a second catcher 34 provided on the slide engages the coupon held by the pawl 33 and moves the same a further step toward the right, until it is engaged by a second pawl 35. By means of some additional catchers 25 and corresponding pawls coupon after coupon is in the described manner fed into the slot 26 and associated with the respective sets of cigarettes. The slide 30 may be reciprocated in any suitable manner for instance by means of a cam or groove-disc and a motion transmitting device (not shown).

Among the advantages of the described portioning device the following may be mentioned. In contradistinction to portioning devices of that type in which the guide-ways also at the assembling place are vertical and for that reason require counter-pistons which are moved upwards and downwards and support the cigarettes while lowered to 40 the assembling place, the construction of the present portioning device is more simple, because no such counter-pistons are necessary. For that reason the present portioning device operates in a more reliable manner. 45 Further it may be mentioned, that, while the set of cigarettes is transmitted into the compression chamber mentioned above, the set of cigarettes can not collapse. The locking means shown in the drawing for retaining 50 the cigarettes in the guide-ways is very simple and not able to spoil the cigarettes. The assembled set of cigarettes may easily be inspected and the supplying of the same with coupons is easily effected.

55 Instead of the drums feeding the cigarettes from the magazine any other feed device,

evidently, may be used, for instance endless belts or the like provided with pockets. The coupons etc. may be cut from a strip. The part of the strip constituting the coupon etc. 60 may be cut from the strip either before the strip, fed forward in any suitable manner, arrives to the set of cigarettes, the part cut from the strip being then introduced into the slot 26, or after the end of the strip 65 has been introduced into the said slot. The coupon etc. may be placed above or under the set of cigarettes or at one of its sides instead of inside the set as shown. The invention may evidently be modified in many 70 other ways without exceeding the limits of the same.

We claim:

1. In a device for portioning staff-shaped articles for the packing of same the combination of guide-ways for the said articles which at an assembling place extend in a substantially horizontal direction and are located above each other, so that the articles are gathered in parallel superposed rows, a piston for pushing a set of articles out from the said assembling place, members provided at the assembling place and means for forcing the said members against those articles, which are located nearest to the set of articles 80 in each guide-way in order to retain the articles in the guide-ways during the return stroke of the piston.

2. In a device for portioning staff-shaped articles for the packing of same and for incorporating a coupon, photo or the like to each set of articles the combination of guide-ways for the said articles which at an assembling place extend in a substantially horizontal direction and are located above each other, so that the articles are gathered in parallel superposed rows, a slide reciprocated at a magazine containing the coupons and provided with yielding members located behind each other and adapted to catch a coupon in the magazine and to transport the same onto the gathered set of articles, stationary members adapted to engage the coupon and hold the same in its new position, while the slide returns, and a piston for pushing a set of articles together with the coupon out from the said assembling place.

In testimony whereof we have affixed our signatures.

GUNNAR CHRISTIAN EKSTRÖM.
